UNITED STATES PATENT OFFICE.

GEORGE Q. ADAMS, OF QUINCY, ILLINOIS.

DESIGN FOR A FENCE-PICKET.

SPECIFICATION forming part of Design No. 15,981, dated March 24, 1885.
Application filed July 24, 1884. Term of patent 3½ years.

To all whom it may concern:

Be it known that I, GEORGE Q. ADAMS, of Quincy, county of Adams, State of Illinois, a citizen of the United States, have invented a new and useful and original Design for Fence-Pickets, of which the following is a specification, reference being had to the accompanying drawings, forming part of this specification.

10 Figure 1 is a front elevation of my design for fence-picket. Fig. 2 is a sectional view through line $x\ x$, Fig. 1.

The leading features of my design for a picket are the surface ornamentation of the same, representing an angular corrugation, bounded on the sides by curved edges, a diamond-pointed top, and a right-angular bottom; and my design consists in a picket having this shape or configuration.

20 A is the picket, which is bent at b inward

on an angle to e and outward to f , inward to g and outward to h , and inward to i and outward to j , having curved edges. The picket thus presents the appearance of an angular corrugated surface. 25

Having described my invention, I desire to claim—

The design for a fence-picket having an angular corrugated surface, bounded upon the sides by curved edges, and provided with a diamond-pointed top and right-angular bottom, as described and shown. 30

Signed at New York, in the county of New York and State of New York, this 23d day of July, A. D. 1884.

GEORGE Q. ADAMS.
